(57) **CLAIM**

The ornamental design for a chair, as shown and described.

DESCRIPTION

FIG. 1 is a front perspective view of a chair showing my new design;

FIG. 2 is a right side view thereof, a left side view thereof being a mirror image;

FIG. 3 is a front view thereof;

FIG. 4 is a rear view thereof;

FIG. 5 is a top view thereof;

FIG. 6 is a bottom view thereof;

FIG. 7 is a cross-sectional view taken along the line 7-7 in FIG. 2; and,

FIG. 8 is a cross-sectional view taken along the line 8-8 in FIG. 4.

The broken lines shown in the drawings illustrate portions of the chair that form no part of the claimed design.
